[57] CLAIM

The ornamental design for a fragrance diffuser housing, as shown and described.

DESCRIPTION

FIG. 1 is a front, top, and right side perspective view of a fragrance diffuser housing showing my new design; FIG. 2 is a front elevation view thereof; FIG. 3 is a right side elevation view thereof, the opposite side being a mirror image of that shown; FIG. 4 is a rear elevation view thereof; FIG. 5 is a top plan view thereof; and FIG. 6 is a bottom plan view thereof.

The broken lines in the drawings are for illustrative purposes only and form no part of the claimed design.
